(57) **CLAIM**

The ornamental design for an elf baby doll, as shown and described.

DESCRIPTION

FIG. 1 is a left side exploded view of an elf baby doll with the hat shown separately for clarity of view;

FIG. 2 is a front exploded view thereof;

FIG. 3 is a right side exploded view thereof;

FIG. 4 is a rear exploded view thereof;

FIG. 5 is a left side view of the elf baby doll of FIG. 1 with the hat in a use configuration;

FIG. 6 is a front view thereof;

FIG. 7 is a right side view thereof;

FIG. 8 is a rear view thereof; and,

FIG. 9 is a front perspective view thereof.

The evenly spaced broken lines within FIGS. 4 and 8 depict portions of the elf baby doll that form no part of the claimed design.
